[57] CLAIM

The ornamental design for a ground effect vehicle, as shown and described.

DESCRIPTION

FIG. 1 is a perspective view of a ground effect vehicle showing my new design;

FIG. 2 is a top plan view of the design, the tail unit of which is a double tail unit;

FIG. 3 is a front elevational view of the ground effect vehicle, the tail unit of which is a double tail unit;

FIG. 4 is a right side view of the design, the tail unit of which is a double tail unit;

FIG. 5 is a bottom plan view of the design, the tail unit of which is a double tail unit;

FIG. 6 is a rear view of the design, the tail unit of which is a double tail unit;

FIG. 7 is a perspective view of a ground effect vehicle showing a second embodiment of my new design;

FIG. 8 is a top plan view of the design, the tail unit of which is a single tail unit;

FIG. 9 is a front elevational view of the ground effect vehicle, the tail unit of which is a single tail unit;

FIG. 10 is a right side view of the design, the tail unit of which is a single tail unit;

FIG. 11 is a bottom plan view of the design, the tail unit of which is a single tail unit; and,

FIG. 12 is a rear view of the design, the tail unit of which is a single tail unit.
